FINGER RING

John L. Hazelquist, Garden City, Mich., assignor to Traub Manufacturing Company, Detroit, Mich., a corporation of Michigan

Filed Jan. 30, 1964, Ser. No. 78,435

Term of patent 14 years

(Cl. D45—10)

FIG. 4

FIG. 3

FIG. 1

FIG. 2

FIGURE 1 is a front elevational view of a finger ring showing my new design;

FIGURE 2 is a rightside elevational view thereof;

FIGURE 3 is a top plan view thereof; and

FIGURE 4 is a perspective view thereof.

The left side elevational view of the finger ring shown in the drawing would be identical to the right side elevational view of FIGURE 2.

The characteristic features of the design reside in approximately the upper one-third of the ring excluding the prongs and including the split structure at the upper portion of the ring and the axially extending through opening defined by the split structure and the outer surface of the circular band portion, all as shown in the drawing.

I claim:

The ornamental design for a finger ring, substantially as shown and described.
